UNITED STATES PATENT OFFICE.

RALPH G. LOCKETT, OF MILWAUKEE, WISCONSIN, ASSIGNOR TO THE CUTLER-HAMMER MFG. CO., OF MILWAUKEE, WISCONSIN, A CORPORATION OF WISCONSIN.

CONTROLLER FOR MOTOR-DRIVEN APPARATUS.

Application filed May 31, 1921, Serial No. 473,897. Renewed January 9, 1928.

This invention relates to controllers for motor driven apparatus and is particularly applicable to controllers for washing machines although it has various other advantageous applications.

In washing machines of the barrel type wherein the direction of rotation of the barrel is periodically reversed considerable difficulty has heretofore been experienced in arresting the barrel with the removable cover thereof in registration with the removable cover of its enclosing casing. Heretofore it has been customary to resort to inching to effect registration of the covers.

The present invention has among its objects to provide control means for washing machines and apparatus of other character which will automatically insure accurate stopping of the driven element in the desired position regardless of its direction of operation at the instant of stopping.

Another object is to provide automatic control means for machinery operating at varying speeds which will insure a predetermined speed upon initiation of the operation of stopping means.

Various other objects and advantages of the invention will hereinafter appear.

The accompanying drawing diagrammatically illustrates one embodiment of the invention which will now be described, it being understood that the controller illustrated is susceptible of various modifications and various different uses without departing from the scope of the appended claims.

Referring to the drawing there is illustrated a barrel 1 to be periodically rotated in opposite directions by a motor M, said barrel having a hinged cover 2 to be brought into registration with an opening in an enclosing case 3, said casing having a removable cover 4.

The motor M is of the shunt type comprising an armature a and field f , said motor to be controlled through the medium of series resistances R , R' and R^2 . As shown the continuity of the motor circuit is controlled by an electro-responsive switch 5 which also controls the circuit of the winding B of an electro-magnetic brake associated with the motor while the direction of operation and speed of the motor are controlled by a drum 6 of conventional form commonly employed for washing machine control. The drum 6 is adapted to be rotated continuously in a

single direction by a pilot motor M' to periodically reverse the flow of current through the motor armature and to control the resistances R , R' and R^2 . As will be understood, whenever the drum 6 reverses the flow of current through the motor armature, it first re-includes the resistances and after reversal automatically excludes said resistances sequentially to accelerate the motor.

The main switch 5 is controlled by an electro-responsive relay 7 which in turn is controlled by a normally open push button switch 8 and a normally closed push button switch 9, said switches respectively serving for starting and stopping. More specifically closure of switch 8 completes a circuit from line L' through said switch by conductor 10 through the winding of relay 7 by conductor 11 through the normally closed switch 9 to line L^2 . The relay 7 is thereupon energized and upon response completes circuit from line L' by conductor 12 through the left hand pole of said relay by conductor 13 through the operating winding of switch 5 to line L^2 . The right hand pole of the relay completes a circuit shunting the switch 8 or in other words establishes a maintaining circuit for said relay independent of the starting switch 8, said circuit being obvious. Thus momentary depression of the switch 8 serves to complete the circuit of motor M whereas momentary depression of switch 9 through de-energization of relay 7 tends to de-energize switch 5 for interruption of the motor circuit. Also there is shown an automatic switch 14 included in the maintaining circuit of the relay for limiting the operation of the motor M to a definite period by periodically initiating the stopping operation, the use of such switch being optional. Such time switches are commonly desired in washing machine control and are so designed as to remain open only momentarily, reclosure thereof being accomplished before the machine is stopped.

While de-energization of the relay 7 tends to de-energize main switch 5, the means now to be described delays de-energization of said switch until the barrel 1 first attains a given speed and then assumes a given angular position according to its direction of rotation. This means comprises an auxiliary contact drum 15 associated with the drum 6 and a contact drum 16 associated with the barrel 1. The drum 15 comprises

two contact segments 17 and 18 insulated from one another and rotatable in unison with the drum 6, the segment 17 having co-operating contact fingers 19 and 20 and segment 18 having co-operating contact fingers 21 and 22. Likewise the drum 16 comprises two contact segments 23 and 24 insulated from one another and rotatable in unison with the barrel 1, said segment 23 having 10 co-operating contact fingers 25 and 26 and segment 24 having co-operating contact fingers 27 and 28. These drums are provided to jointly establish a number of alternative shunts for the relay 7 to maintain 15 the switch 5 energized upon release of said relay. More specifically, the intermediate fingers of the two drums are interconnected through a common connection 29 while the fingers 19 and 22 of drum 15 are respectively connected to fingers 28 and 25 of drum 16 by conductors 30 and 31. Also fingers 22 and 25 are connected by conductors 32 and 12 to line L' while fingers 19 and 28 are connected by conductor 33 to conductor 13 and through the winding of switch 5 to line L'. Thus it will be apparent that the two drums afford a number of combinations for establishment of a maintaining circuit for switch 5.

30 However, the segments 17 and 18 of drum 15 are interrupted as by insulation inserts 34 and 35 respectively whereby one segment breaks circuit between its co-operating contact fingers in a full speed forward 35 position of the drum 6 and the other in a full speed reverse position of said drum. Also the segments 23 and 24 of drum 16 are interrupted as by insulation inserts 36 and 37 to respectively interrupt circuit between 40 their co-operating fingers as the barrel 2 approaches from the opposite directions the angular position illustrated. Thus by proper design of the drums and proper co-ordination of the sections thereof, the 45 same may be caused to interrupt all of the possible shunts around relay 7 but only when the motor M is operating at full speed or any other preferred speed and when the cover of the barrel 1 is at a given distance 50 from the position illustrated.

The main switch 5 when thus de-energized interrupts the circuit of motor M and de-energizes the brake coil B with a consequent tendency to effect immediate stopping of the barrel and in view of the fact that the switch 5 releases only at a given speed of the motor, the drift, if any, will be substantially uniform. Manifestly therefore, the means described provides for 55 accurate stopping of the barrel regardless of its speed and direction of operation at the instant of release of relay 7 under the influence of the time switch 14 or the manual stop switch 9. It is to be understood 60 that the brake may be so designed as to stop

the barrel in the desired position regardless of variations in load within a fairly wide range if the barrel is always accelerated to a given speed prior to stopping as described.

More specifically considering the connections controlled by the drums 15 and 16 circuit may be traced from line L' by conductors 12, 32 and 31 to and through contact finger 22, segment 18 and contact finger 21 of drum 15 and thence to and through contact finger 20, segment 17 and contact finger 19 by the conductors 30, 33 and 13 to and through the winding of switch 5. Also circuit may be traced from contact finger 21 by conductor 29 to and through contact finger 27, segment 24 and contact finger 28 of drum 16 to conductors 33 and 13 thus paralleling the circuit through segment 17 and contact fingers 19 and 20. Obviously therefore assuming an uninterrupted connection between contact finger 20 and line L' the switch 5 is insured energization until the insulating insert 34 of drum 15 registers with contact finger 19 and the insulated insert 36 of drum 16 simultaneously registers with contact finger 28 which will occur when the drum 6 assumes a position for given speed of motor M and barrel 1 assumes a given angular position as aforescribed. As will be apparent the drum 15 may be operated at such a speed as to permit a full revolution of drum 16 during the period that insulating insert 34 of the former drum registers with contact finger 19 whereby de-energization of switch 5 may be insured when the barrel 1 assumes a given angular position causing the insulating insert 36 to register with contact finger 28. Also as will be apparent the segment 18 of drum 15 serves to maintain line connection of contact 20 throughout operation of the barrel 1 in a given direction since the insulating insert 35 is 180 degrees removed from the insulating insert 34 to function only upon operation of the drum 6 for reverse operation of motor M.

Also circuit may be traced from line L by conductors 12 and 32 to and through contact finger 25, segment 23 and contact finger 26 of drum 16 and by conductor 29 to contact finger 20 of drum 15. Thus assuming an uninterrupted connection between the winding of switch 5 and contact finger 20, said winding is insured connection to line L' so long as segment 18 bridges contact fingers 21 and 22 or segment 23 bridges contact fingers 25 and 26. On the other hand when contact fingers 22 and 25 simultaneously engage the insulating inserts of their respective contact segments they insure interruption of the circuit of winding 5, this occurring when the drum 6 assumes a position for a given speed of motor M and the barrel 1 occupies a given angular position. As will be apparent the segment 17

provides an uninterrupted connection between contact finger 20 and the winding of switch 5 throughout operation of the barrel in a direction opposite to that previously assumed.

What I claim as new and desire to secure by Letters Patent is:

1. In a controller for motor driven apparatus, in combination, means to direct stopping of the driving motor and means tending to render the former means ineffective for stopping pending given positioning of a part of the driven apparatus and concurrent operation of the driving motor at a given speed.

2. In a controller for motor driven apparatus, the apparatus being operable in opposite directions by reversal of the motor, in combination, means to direct stopping of the driving motor and means tending to render the former means ineffective for stopping pending given positioning of a part of the driven apparatus depending upon its direction of operation and also pending concurrent operation of the motor at a given speed.

3. In a controller for motor driven apparatus, in combination, means to effect operation of the motor in opposite directions and to accelerate the motor and stopping means for the driving motor including means for delaying initiation of the stopping operation pending given positioning of a part of the driven apparatus varying with the direction of operation thereof and pending concurrent operation of the motor at a given speed.

4. In a controller for motor driven apparatus, in combination, means for periodically reversing the driving motor and automatically accelerating the same, means to direct stopping of the motor and means tending to render said stopping means ineffective for stopping pending given acceleration of the controlled motor and movement of a part of the driven apparatus into given positions selectively according to the direction of operation of the motor.

5. In a controller for motor driven apparatus, in combination, means for periodically reversing the driving motor and accelerating the same, means independent of the former means to direct stopping of the motor and means tending to render said stopping means ineffective for stopping pending given acceleration of the controlled motor and movement of a part of the driven apparatus into given positions selectively according to the direction of operation of the motor, said first mentioned means being operable to stop the motor for reversal independently of the last mentioned means.

6. In a controller for motor driven apparatus, in combination, means to start and accelerate the driving motor and stopping means for the motor including devices re-

spectively associated with the driven apparatus and said accelerating means to delay action of said stopping means pending given positioning of a part of the driven apparatus and concurrent operation of the motor at a given speed.

7. In a controller for motor driven apparatus, in combination, means for starting and accelerating the driving motor, said means providing for reversal of the direction of operation of the motor and stopping means for the motor including devices respectively associated with the driven apparatus and said accelerating means to delay action of said stopping means pending given positioning of a part of the driven apparatus, such positioning varying with the direction of operation of the motor and also pending concurrent operation of the motor at a given speed.

8. In a controller for motor driven apparatus, in combination, means for starting and accelerating the driving motor, said means providing for reversal of the motor periodically and stopping means for the motor including devices respectively associated with said accelerating means and the driven apparatus to render action of said stopping means dependent upon given positioning of a part of the driven apparatus such positioning varying with the direction of operation of the motor and also dependent upon concurrent operation of the motor at a given speed, said first mentioned means being operable to stop the motor for reversal thereof independently of the last mentioned means.

9. In a controller for motor driven apparatus, in combination, means to start, accelerate and stop the driving motor including an electro-magnetic switch to be de-energized for stopping and devices respectively associated with the driven apparatus and said accelerating means to maintain an energizing circuit for said stopping switch throughout a given range of movement of a part of the driven apparatus regardless of the speed of the motor and to interrupt such circuit only under given speed conditions.

10. In a controller for motor driven apparatus in combination, means to start and accelerate the driving motor and to vary the direction of operation thereof, independent stopping means for the motor including an electro-magnetic switch to be de-energized for stopping, and devices respectively associated with the driven apparatus and said accelerating means to provide maintaining circuits for said switch whereby stopping by the latter is delayed pending predetermined positioning of a part of the driven apparatus according to the direction of operation of the motor and also pending concurrent operation of the motor at a given speed.

11. In a controller for motor driven apparatus, in combination, means to direct stopping of the driving motor and means tending to render the former means ineffective for stopping pending given positioning of a part of the driven apparatus and concurrent operation of the driving motor at substantially full speed.
12. In a controller for motor driven apparatus, in combination, means for periodically reversing the driving motor and automatically accelerating the same, said accel-

erating means comprising resistance to be excluded from the motor circuit, means to direct stopping of the motor and means tending to render said stopping means ineffective for stopping pending exclusion of all of said resistance from the motor circuit and given positioning of a part of the driven apparatus.

In witness whereof, I have hereunto subscribed my name.

RALPH G. LOCKETT.
